DESIGN.

J. W. HOODWIN.

ICE CREAM CONE TRAY.

APPLICATION FILED JULY 9, 1921.

60,025.

Patented Dec. 20, 1921.

Inventor:
Joseph W. Hoodwin
By G. S. Sims, atty.

UNITED STATES PATENT OFFICE.

JOSEPH W. HOODWIN, OF CHICAGO, ILLINOIS, ASSIGNOR TO J. W. HOODWIN COMPANY, OF CHICAGO, ILLINOIS, A CORPORATION.

DESIGN FOR AN ICE-CREAM-CONE TRAY.

60,025.

Specification for Design.

Patented Dec. 20, 1921.

Application filed July 9, 1921. Serial No. 483,575. Term of patent 7 years.

To all whom it may concern:

Be it known that I, JOSEPH W. HOODWIN, a citizen of the United States of America, residing at Chicago, in the county of Cook and State of Illinois, have invented a new, original, and ornamental Design for an Ice-Cream-Cone Tray, of which the following is a specification, reference being had to the

accompanying drawing, forming a part thereof.

The figure is a plan view of a tray showing my new design.

I claim:

The ornamental design for an ice cream cone tray as shown.

JOSEPH W. HOODWIN.
